UNITED STATES PATENT OFFICE.

THEODORE G. RUTH, OF STERLING, ILLINOIS, ASSIGNOR OF ONE-HALF TO
WILLIAM F. EASTMAN, OF SAME PLACE.

PRINTING-MACHINE.

SPECIFICATION forming part of Letters Patent No. 245,566, dated August 9, 1881.

Application filed May 7, 1881. (No model.)

To all whom it may concern:

Be it known that I, THEODORE G. RUTH, a citizen of the United States, residing at Sterling, in the county of Whiteside and State of Illinois, have invented certain new and useful Improvements in Printing-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in newspaper-printing machines, and has special reference to certain new and useful mechanism, whereby the name and address of a subscriber can be printed upon a conspicuous place on such newspaper, for mailing, coincidently with the process of printing the paper.

In the drawings, Figure 1 is a side elevation of part of a printing-machine provided with my invention. Fig. 2 is an elevation of printing-machine cylinder in connection with my invention. Fig. 3 is an end view of the galley-bed G, the galley H, for holding the names and addresses in type, and the pawl-bar I, for moving such galley. Figs. 4 and 5 are detached views of the galley H and pawl-bar I.

Referring to Fig. 1, A is the ordinary cylinder of a newspaper-press, which carries the paper to and from the types. B is the feed-table. C represents the newspaper after being printed, leaving the cylinder A and passing over the address-types p.

In the art the mechanism employed for feeding the paper to the press and carrying it therefrom is so well known that I do not deem it necessary to exhibit or describe any more parts thereof than will clearly show the mode of attachment and the operation of my invention.

D is a vibratory arm, rigidly attached at its upper end to the transverse oscillating bar E of the press-frame, as shown in Fig. 2. The lower end of the arm D is provided with a plate, a, parallel with the surface of the address-types p, and the use of the plate a is to press the newspaper down upon such address-

types, to obtain an impression therefrom while 50 the paper is passing from the machine.

The bar E, as shown in Fig. 2, is journaled near each end in the frame of the press, and is provided at one end with the short projecting arm b, rigidly attached thereto.

F is the ordinary cog-wheel, affixed rigidly to the axle of the cylinder A, and through which motion is communicated to such cylinder. On the inside of the wheel F is affixed the pin or cam d, which engages and actuates 60 the arm b on the bar E at each revolution of the cylinder A, thus partially revolving the bar E, which action gives to the arm D a downward motion, bringing the plate a against the paper C, and impressing the latter upon 65 the address-types p. As the wheel F and cylinder A are both rigidly seated upon the same axle their revolutions are coincident, and where each revolution of the cylinder A prints one paper one action of the arm D to each of 70 such revolutions is sufficient, and the number of pins d may be increased to correspond with the number of papers printed at each revolution of the cylinder A. The coiled spring e withdraws the arm D after each action of the 75 latter.

The following is the mechanism for feeding the address-types p: A galley-bed G, extends transversely across the front of the press under the feed-table B, the end of which bed is 80 shown in Fig. 3. This galley-bed G is fitted to receive the galley H and the pawl-bar I. The back of each galley H is fitted to have attached thereto a ratchet-plate, f. This can be done in any suitable way. My present mode is to form 85 short studs on the back of the galley to fit into corresponding holes in the ratchet-plate f, so that the latter may be readily attached to or detached from the galley H. As the galley-bed G lies nearly horizontal the weight of the 90 galley H holds the plate f in position. The pawl-bar I is actuated by a lever, K, fulcrumed on the press-frame at g, and having a friction-roller, h, at its outer end, arranged to be engaged by a cam, i, on the outer side and near 95 the periphery of the wheel L. The wheel L is rigidly placed on the axis of the cylinder A, at the end thereof, opposite to the wheel F, and

therefore makes the same number of revolutions as does the cylinder A. As suggested hereinbefore in reference to the impinging arm D, should more than one paper be printed in 5 one revolution of the cylinder A, the number of cams *i* on the wheel L can be correspondingly increased.

The names and addresses of the subscribers, in the alphabetical order of their post-offices, 10 are set up in a column in the galley H. The latter, having attached thereto the ratchet-plate *f*, is placed in the galley-bed G, and the end of the pawl-bar I inserted between the back of the galley H and the face of the galley-bed G, as 15 shown in Fig. 3, in a recess formed in the face of such galley-bed, to receive the pawl-bar I, the latter being so far inserted that the pawl *k* will engage one of the ratchets of the ratchet-plate *f* at or near the end of the galley H 20 farthest from the actuating-lever K. At each revolution of the wheel L the cam *i* thereon strikes the friction-pulley *h*, thus driving the outer end of the lever K outward, and its inner end, to which is attached the pawl-bar 25 I, inward. The pawl *k* engages one of the ratchets of the plate *f*, and the galley H is thereby moved endwise one degree. This motion is so arranged as to be in distance the scope 30 of the name and address of one subscriber as set up in type in the galley H. A spring, *l*, attached to the lever K and side of the press, returns such lever, after it has passed the cam *i*, to the face of the wheel L, thus drawing the pawl *k* into the next ratchet. A cover, *m*, ex- 35 tends over all of the galley H, except an open-

ing, *n*, near the center thereof, of sufficient width to expose one name and address. The opening *n* is directly under the point of impact of the plate *a* of the arm D, and such plate *a* passes into such opening. Thus is assured the 40 printing of but one name and address at a time. At each successive action of the pawl-bar I the succeeding name and address in the galley H are presented at the opening *n*.

My invention may be placed at such points 45 in relation to the cylinder A, as to print the name and address of the subscriber at any place on the paper that may be desired. When arranged as shown the name and address are printed at the top of the title-page. 50

What I claim as my invention, and desire to secure by Letters Patent of the United States, is—

1. The galley H, provided with the ratchet-plate *f*, the pawl-bar I, the lever K, and the 55 wheel L, provided with the cam *i*, in combination with the impacting-arm D, substantially as shown, and for the purpose aforesaid.

2. As an attachment to a printing-machine, the galley-bed G, the galley H, the pawl-bar I, 60 the lever K, and wheel L, having the cam *i*, in combination, substantially as shown, and for the purpose described.

In testimony whereof I affix my signature in presence of two witnesses.

THEODORE G. RUTH.
